United States Patent Office

Des. 210,926
Patented May 7, 1968

210,926

FOOTBALL VEST

William P. Dickens, Bloomington, Ind., assignor to Indiana University Foundation, Bloomington, Ind.,
a corporation of Indiana

Filed June 1, 1967, Ser. No. 7,329

Term of patent 14 years

(Cl. D2—27)

The bottom is substantially plain and unornamented.
I claim:

The ornamental design for a football vest, substantially as shown and described.
